Attorney.

UNITED STATES PATENT OFFICE.

JOHN W. BARNHART, OF GRAND RAPIDS, MICHIGAN, ASSIGNOR, BY MESNE ASSIGNMENTS, TO KELVINATOR CORPORATION, OF DETROIT, MICHIGAN, A CORPORATION OF MICHIGAN.

COLD-AIR DEFLECTOR.

Application filed September 21, 1925. Serial No. 57,539.

This invention relates to a cold air deflector particularly applicable to refrigerators. In refrigerators, when the door to the ice chamber is opened, there is a tendency for the cold air within the refrigerator and around the ice to pass outwardly through the door opening and, by reason of its heaviness, to pass downwardly over the front of the refrigerator below the ice chamber door opening, whereby a condensation of moisture against the front surface of the refrigerator occurs. This is very detrimental to the construction of the refrigerator casing, injuring the varnished finish thereof and eventually swelling the joints between the pieces of wood making up the front frame of the case, the alternate swelling and shrinking at said joints causing a rapid deterioration of the refrigerator case construction and its appearance at the front, as is evident.

The present invention is concerned with an extremely simple means for deflecting the cold air which normally would pass outwardly and downwardly through the ice chamber door opening when the door is opened, so that instead it passes downwardly inside of the cold air deflector, under the ice holding rack within the ice chamber and downwardly through the flue between the ice chamber and one of the provision chambers located directly below said ice chamber. This results not only in the elimination of moisture condensation with the resultant detrimental effects to the refrigerator casing but also results in a saving of ice in that the cold air is saved from dissipation and warm air to take its place does not have to be refrigerated and have its heat removed, with the resultant expenditure of ice to effect such result.

It is a primary object and purpose of the present invention to provide a cold air deflector of the simplest form and construction which is readily applied to the refrigerator at the front lower portion of the ice chamber, which can be applied without the use of tools of any sort and which can be as easily removed when necessary for the introduction of ice into the ice chamber. To these ends as well as others not at this time specifically stated I have made the construction illustrated in the accompanying drawing, in which,

Fig. 1 is a perspective view of a refrigerator having its doors opened and showing the cold

air deflector located at the front lower portion of the ice chamber.

Fig. 2 is a somewhat enlarged vertical section through the refrigerator, the section being taken through the ice chamber and the provision compartment directly beneath it,

Fig. 3 is an enlarged perspective view of the cold air deflector.

Like reference characters refer to like parts in the different figures of the drawing.

The refrigerator 1 may be of any well-known type of construction and in that shown it includes an elongated vertical provision compartment 2 at one side occupying substantially one-half of the inner space of the refrigerator, while at the opposite side is an ice chamber 3 located at the upper corner of the refrigerator, below which is a second smaller provision compartment 4. These various chambers and compartments have openings at the front through the refrigerator casing which may be closed by doors 5, 6 and 7, respectively, hingedly mounted so that the same may be swung from open to closed position or vice versa.

A horizontal partition 8 divides the ice chamber 3 from the lower and smaller provision compartment 4, there being a vertical flue 9 through said partition connecting the ice chamber with the compartment 4. Also a lateral flue 10 is made through the refrigerator lining between the smaller provision compartment 4 and the larger provision compartment 2 near the lower end of the latter, and a third flue 11 is made through the refrigerator linings of the compartment 2 and the ice chamber at the upper ends thereof. With ice in the ice chamber the cold air passes from the ice downwardly through the flue 9, thence laterally through the flue 10, upwardly through the provision compartment 2, and thence laterally through the flue 11 back to the ice, there being a continuous circulation of the air which is continuously cooled by the ice.

When the door 6 to the ice compartment is opened normally the cold air will pass from the ice compartment outwardly at the lower end of the door opening and downwardly over the outer surface of the front of the refrigerator casing, warm air from the outside passing into the ice compartment at the upper end of the door opening. The frame

at the front of the refrigerator on which the doors are mounted includes a horizontal cross member 12 located at the front edge of the partition 8, the member 12 having a portion 5 extending above the upper side of said partition. The door openings are defined by this horizontal partition and a vertical partition 13 located substantially midway between the sides of the refrigerator. This partition 13 10 has edge portions extending inwardly from each side of the vertical parts of the refrigerator lining between the provision compartment 2 at one side of the refrigerator and the ice chamber and compartment 4 at the opposite side of the refrigerator. Likewise that part of the casing on which the door 6 is hingedly mounted has inwardly extending portions projecting inward beyond the lining 15 of the ice chamber.

- 20 20 The cold air deflector which I have devised comprises a rectangular plate of sheet metal 14, at its upper and lower edges, being turned back upon itself, as indicated at 15, for a short distance so as to make smooth 25 edges which will not injure the fingers of one handling the same. The length of this plate is slightly less than the distance between the opposite sides of the lining to the ice chamber whereby it may be located vertically in the 30 ice chamber between the sides of the ice chamber lining. This length however is greater than the width of the door opening for the door 6 so that the ends of the member 14 bear against the rear side of the vertical part 13 and the rear side of the inwardly 35 projecting portion of the case where the door 6 is hingedly mounted. The lower edge of the deflector 14 rests against the lining placed over the partition 8 and back of that portion 40 of the cross member 12 of which extends above the partition 8. The ice is carried on an ice rack 16 and the deflector is located at the front of the ice chamber and in front of the ice rack, it being of a width such that it 45 extends a distance upward approximately one-quarter to one-third of the height of the ice chamber door, though the particular height to which the deflector may extend may be varied considerably.
- 50 50 The deflector 14, it is evident, may be readily placed in position without the use of any tools whatever and the same may be removed whenever it is desired quite as easily. It is removed during the time when the ice 55 is being placed in the ice chamber and then immediately put back in position. The cold air tending to drop downwardly and thence outwardly through the door opening to the ice chamber passes back of the deflector 14 60 and downwardly and under the ice rack 16 through the flue 9 and thence through the flues 10 and 11, being deflected from passing outwardly and downwardly over the outer face of the refrigerator casing.
- 65 65 This very simple device applied as shown

and described is particularly useful in this relation. Its simplicity of construction and application to the refrigerator makes it very economical from a manufacturing standpoint and particularly convenient to use. The saving of the cold air is one advantage of the device while the prevention of moisture condensation against the front of the refrigerator connection below the ice chamber door opening is of great value especially if the ice chamber door should not fit tightly or to be left slightly ajar. The invention fully secures both of these advantages and has proved its practical merit for a considerable time in actual practice. The invention is defined in 80 the appended claims and is to be considered as comprehensive of all forms of structure coming within their scope.

I claim:

1. In a refrigerator having an upper ice chamber and a lower provision compartment directly below the ice chamber with a partition having a flue opening through the same disposed horizontally between the ice chamber and said provision compartment, said ice chamber having an opening at the front adapted to be closed by a door, of an unattached plate vertically positioned in the front lower portion of the ice chamber and supported at its lower edge against the upper side of said partition, said plate being of greater width than the door opening and extending upwardly a portion of the height of the door opening and being freely removable from and replaceable in the ice chamber through the door opening.

2. In a refrigerator having an upper ice chamber and a provision compartment directly below the ice chamber with a horizontal partition disposed between the ice chamber and provision compartment having a vertical flue opening therethrough, and said ice chamber at its front having an entrance opening normally closed by a door, of an unattached plate having a width greater than the distance between the vertical edge of the opening and shorter than the distance between the sides of the ice chamber disposed vertically at the front lower portion of the ice chamber and at its lower edge being supported by said horizontal partition, said plate being free from connection to any part of the refrigerator and removable through said door opening.

3. In combination with a refrigerator having an ice chamber provided with a door opening at its front side and a door hingedly connected to the refrigerator to close said door opening, and with an ice rack located in the lower portion of said ice chamber, of a cold air deflector plate located vertically in the front lower portion of the ice chamber and in front of the front edge of said ice rack, said plate extending above said ice rack and covering the lower portion of said door open-

ing and being freely removable from and replaceable in said ice chamber.

4. In combination with a refrigerator having an ice chamber provided with a door opening at its front side and a door hingedly connected to the refrigerator to close said door opening, and with an ice rack located in the lower portion of said ice chamber, of a cold air deflector plate having a greater width than the width of the door opening and located vertically in the front lower portion of the ice chamber and in front of the front edge of said ice rack, said plate extending above said ice rack and covering the lower portion of said door opening and being freely removable from and replaceable in said ice chamber.

5. In combination, a refrigerator having walls defining a cooling compartment one of said walls having an opening therethrough affording access to said compartment, and a door for closing the opening in said wall; an ice supporting rack at the bottom of said compartment; and an unattached cold air deflector plate of greater width and less height than the opening affording access to said compartment, said plate being maintained in upright position intermediate said rack and the wall of said compartment having the opening therein and being removable through the wall opening.

In testimony whereof I affix my signature.

JOHN W. BARNHART.
